MOBILE

Marilea Sue Smith, 5508 Indianola, Indianapolis, Ind.

Filed Aug. 31, 1964, Ser. No. 81,724

Term of patent 14 years

(Cl. D29—1)

FIG. 4.

FIG. 1 is a perspective view of a mobile embodying my new design;

FIG. 2 is a side elevation thereof;

FIG. 3 is a rear elevation thereof;

FIG. 4 is a front elevation of a modified form of the mobile shown in FIG. 1; and

FIG. 5 is a side elevation of the mobile shown in FIG. 4.

The rear side of the mobile shown in FIGS. 4 and 5 is a mirror image of the side shown in FIG. 4.

The dominant features of my design are shown in full lines.

This application is a continuation-in-part of my co-pending application Serial No. 80,184, filed May 27, 1964, I claim:

The ornamental design for a mobile, as shown and described.
